AUTOMATIC SHAKER SHOVEL

Robert Gibson, New Waterford, Nova Scotia, Canada, assignor of thirty-seven and one-half percent to Joseph Kalbhenn, New Waterford, Nova Scotia, Canada, and thirty-seven and one-half percent to Peacock Brothers Limited, Montreal, Quebec, Canada

Application July 29, 1932, Serial No. 625,899
In Canada July 31, 1931

8 Claims. (Cl. 198—220)

This invention relates to mining apparatus and particularly to means for feeding and loading the shovel section of the shaker shovel type.

The object of the invention is to provide an improved form of feeding and loading means whereby the shovel and its trough section is automatically advanced or retired.

A further object is to provide feeding mechanism which will have greater power, more positive action and less loss of motion than has hitherto been obtainable.

A further object is to produce feeding mechanism of light construction entirely free from fixed supports and situated below the trough surface.

A further object is to provide a feeding mechanism with balanced action which avoids distortion and operates with a minimum of friction.

20 The invention consists briefly in a trough section with shovel extension having wire ropes mounted on both sides between brackets. This trough section slides on a lower reciprocating trough section which carries side pulleys with 25 ratchet wheels and adjustable pawls having the wire ropes looped about the pulleys on each side and adapted when reciprocated in the usual manner to either advance the upper section to retire it or simply to reciprocate together with the 30 lower trough.

Adjacent this feed mechanism is a guide and tensional device having roller or rollers supporting the lower trough and side pulleys, and ratchets, mounted on stub shafts journaled on bearings supported on a base plate. The wire ropes of the upper trough section are also looped in the same manner over these pulleys, the ratchets are controlled by reversing pawls. The plate is mounted on a curved track and means are 35 provided to move the plate sideways on the track.

Reference is made to the accompanying drawings in which:

Figure 1 is a plan view of the controlling apparatus.

45 Figure 2 is a vertical section on the line 2—2 of Figure 1.

Figure 3 is a vertical section on the line 3—3 of Figure 1.

Figure 4 is a side view of the device.

50 Figure 5 is an enlarged detail view of the feeding ratchets.

Figure 6 is a plan view of the complete apparatus.

In Figure 6 the trough 1 is shown with the 55 extension shovel 12, this trough 1 sits in the

lower trough 2 which extends with connections to the reciprocating mechanism which is not shown in the drawings. On each side of the trough 1, between brackets 11, having the usual tension terminals are the ropes 10. The lower trough 2 has cross flat bars 20 welded to its bottom and sides. Brackets 21 are bolted to these bars and support frames 3, these frames 3 comprise inner U-bar 30, outer U-bar 31 and top U-bar 32.

5 A shaft 4 having pulleys 40 and ratchet wheels 41 and 42 keyed to it are journaled in the frame to rotate freely. On one side are a pair of reverse ratchet wheels 41 and 42 while the other pulleys have single ratchet 41. The ratchets have pawls 43, meshing with ratchet wheels 41 and pawl 44 meshing with ratchet wheel 42. The pawls are controlled by a control fork 47, which when raised throws both ratchets out of 10 action, which when moved to the right brings the pawls 41 into action and when moved to the left brings the pawl 44 into action with ratchet wheel 42.

A further object is to provide a feeding mechanism which when moved to the right brings the pawls 41 into action and when moved to the left brings the pawl 44 into action with ratchet wheel 42.

20 The wire ropes 10 are looped over the pulleys 40, and connect the upper trough with the feed mechanism and the lower trough.

25 Adjacent to this feed mechanism is situated a supporting directing and rope tensioning device. This comprises a base plate 5, on which are two sets of bearing standards 50 having bearings 51, 30 in which are journaled stub shafts supporting the pulleys 60, with ratchet wheels 61 and 62 which are reverse ratchets. Pawls 63 and 64 are mounted on and controlled by a pawl rod 65.

35 Secured to the bottom of the lower trough 2 are guide bars 22. Rollers 7 journaled in anti-friction bearings 71, and bearing posts 70, run on these guide rails and support and direct the lower trough 2.

40 The base plate 5 is mounted on a curved track 40 3, extending to each side and having suitable means to adjust it sideways thereon, and the plate 5 can thus be readily moved to either side and the shovel brought to operate on a new area.

45 Figure 5 shows a detail of the reversing pawls 43 and 44, 43 being adjustably controlled while 44 is secured directly to its spindle.

The action of the device is as follows:—

50 When it is desired to feed the shovel forward the pawls 43 and 63 are set to mesh with their ratchets, and the reciprocation of the lower trough 2, causes the upper trough 1, to slide forward on its forward stroke and thus advance by successive steps. If the ratchets of both are 55

released the two troughs will operate together and merely set as a conveyor. When the upper trough has advanced to its limit or it is desired to withdraw it or retire it, the pawls 44 and 64 are adjusted to mesh with their ratchets and the reciprocation of the lower trough will cause the upper trough to retire by successive steps.

As the ropes are looped about two sets of pulleys, the one set reciprocating with the lower trough while the other set is stationary the ropes will be held in proper tension at all times and lost motion avoided. A positive action of the highest efficiency is thereby obtained. The weight of the feeding mechanism is supported by the lower trough which moves on the rollers freely. As it is equally divided on each side there is balanced action and no tendency to distortion or displacement.

The guide bars of the lower trough keep it on the rollers and when the base plate is moved transversely, these bars will bring the lower trough into its new position without strain or friction.

What I claim is:

1. In a device of the class specified the combination of a reciprocating trough section and a shovel trough section mounted to slide thereon and means to feed the second section in either direction, mounted under the first section, having ropes at the sides of the second section adapted to control its movement.

2. In a device of the class specified the combination of a reciprocating trough section and a shovel trough section mounted to slide thereon and means to feed the second section in either direction, mounted under the first section, having ropes at the sides of the second section adapted to control its movement and a stationary roller support adjacent said means having tensioning devices for said side ropes.

3. In a device of the class specified the combination of a reciprocating trough section and a shovel trough section mounted to slide thereon, and having ropes at each side between terminal brackets, frames secured to the first section journaling pulleys and reversing ratchets, with adjustable pawls, the ropes looped around the pulleys.

4. In a device of the class specified the combination of a reciprocating trough section and a shovel trough section mounted to slide thereon, and having ropes at each side between terminal

brackets, frames secured to the first section journaling pulleys and reversing ratchets with adjustable pawls, the ropes looped around the pulleys, with a rope tensioning device, mounted on a stationary roller support adjacent of the 5 said frames.

5. In a device of the class specified the combination of a reciprocating trough section and a shovel trough section mounted to slide thereon, and having ropes at each side between terminal 10 brackets, frames secured to the first section journaling pulleys and reversing ratchets, with adjustable pawls, the ropes looped around the pulleys, with a rope tensioning device, mounted on a stationary roller support adjacent to the said 15 frames, comprising pulleys and reversing ratchets journalled on stub shafts, with the ropes looped on such pulleys.

6. In a device of the class specified the combination of a reciprocating trough section and a shovel trough section mounted to slide thereon, and having ropes at each side between terminal 20 brackets, frames secured to the first section journaling pulleys and reversing ratchets, with adjustable pawls, the ropes looped around the pulleys, with a rope tensioning device and roller support comprising a plate, with rollers mounted in 25 bearings thereon, and stub shafts mounted in bearings, such stub shafts having pulleys and ratchet wheels keyed thereto having adjustable 30 pawls.

7. In a device of the class specified the combination of a reciprocating trough section and a shovel trough section mounted to slide thereon, and having ropes at each side between terminal 35 brackets, frames secured to the first section journaling pulleys and reversing ratchets, with adjustable pawls, the ropes looped around the pulleys, with a rope tensioning device and roller support comprising a plate with rollers mounted in 40 bearings thereon, and stub shafts mounted in bearings, such stub shafts having pulleys and ratchet wheels keyed thereto having adjustable pawls, with an arcuate track supporting the plate.

8. In a device of the class specified, the combination of a reciprocating trough section and a shovel trough section mounted to slide thereon and means to feed the second section in either direction, said means being mounted under the first section, having ropes attached to the second 45 section and adapted to control its movement.

ROBERT GIBSON.
